UNITED STATES PATENT OFFICE.

NATHAN H. DAVIS, OF PHILADELPHIA, PENNSYLVANIA.

DESIGN FOR A METAL BEAM.

SPECIFICATION forming part of Design No. 34,721, dated July 2, 1901.

Application filed May 13, 1901. Serial No. 60,128. Term of patent 14 years.

To all whom it may concern:

Be it known that I, NATHAN H. DAVIS, a citizen of the United States of America, residing in the city and county of Philadelphia, in the State of Pennsylvania, have invented and produced a new and original Design for Metal Beams, of which the following is a specification, reference being had to the accompanying drawings, forming part thereof.

Figure 1 is a perspective view showing a beam having my new design; and Fig. 2 is a cross-section of such a beam, showing my design.

As shown in the drawings, the leading and material feature of my design consists of a metal beam having a generally-cruciform section made up of a web or flange A, two outwardly and oppositely extending flanges A' A',

extending from the base of flange A and substantially perpendicular thereto, and a third arm A², lying opposite to the flange A, having a generally-circular form and connected with the flanges A' by a narrow neck A³.

The principal object or purpose of my newly-designed metal beam, which is of convenient rolled section, is for manufacture into brake-beams.

Having now described my invention, what I claim as new, and desire to secure by Letters Patent, is—

The design for a metal beam as herein shown and described.

NATHAN H. DAVIS.
